UNITED STATES PATENT OFFICE.

GIDEON H. LEEDS, OF WEST CHESTER, AND CHARLES N. THORPE, OF PHILADELPHIA, PENNSYLVANIA.

IMPROVEMENT IN THE STRIKING-WORKS OF CLOCKS.

Specification forming part of Letters Patent No. **139,166**, dated May 20, 1873; application filed February 5, 1873.

To all whom it may concern:

Be it known that we, GIDEON HOWARD LEEDS, of West Chester, in the county of Chester and State of Pennsylvania, and CHARLES N. THORPE, of the city of Philadelphia and State of Pennsylvania, have invented certain Improvements in the Striking-Works of Clocks, of which the following is a specification:

Our invention consists in the lifting-lever, constructed of a single bar, which is formed with a knife-edge, carries the starting and stopping pins, and has its free end lifted by a projection on the hand-arbor in connection with the dividing and other wheels, as will be hereinafter set forth.

To enable others to make and use our improvement in clocks, we will now give a full description thereof.

In the accompanying drawing, which makes a part of this specification, Figures 1 and 2 are side elevations of the frame of a clock having the striking-works constructed and arranged with our improvement. Fig. 3 is an end elevation of the same. Fig. 4 is an edge view of the wheel M and detent-lever T detached from the clock, but arranged in relation to each other as they appear in connection with the clock. Fig. 5 is a side view of dividing-wheel F. Fig. 6 is a side view of the shaft L, having the improved pinion K in position, and the detachable wire j partly withdrawn.

Like letters in all the figures indicate the same parts.

A A are the sides of the standing frame. B B B B are rods which connect the two sides together. C is the driving-shaft, which is provided with the spring D, great-wheel E, and dividing-wheel F. The shaft G is connected with the wheel E by means of its pinion H. The pin-wheel J on said shaft G gears into the pinion K on the shaft L. The wheel M on said shaft L gears into the pinion N on the shaft O; and the wheel P on said shaft O, gears into the pinion Q on the fly-wheel shaft R, thus completing the gearing on the train of shafts, whereby power is communicated from the spring D to the fly-wheel S on the shaft R, and the requisite accelerated speed

in the fly-wheel is produced. T is a detent-lever hung by means of the pin a on the projection b of one of the side frames A. It is operated by means of the bent wire d, which projects from the side of the minute-hand arbor U by the said wire passing under and elevating its inner end e whenever the minute-hand has completed its circuit. The knife-edge f of the lever is allowed to rest on the periphery of the dividing-wheel F, and to engage successfully with the notches g, thus to free or hold the striking-train to cause it to strike the proper number at each hour. This is effected by means of two pins, h h', which project from the inner side of the detent-lever T, so arranged as to connect with the pin i on the contiguous side of the wheel M to lock or to free said wheel at the proper time by the operation of the minute-hand shaft U above described. The arrangement of the pins h h' and i is clearly shown in Fig. 4. The pin i engages with the pin h when the detent is down in its lowest position, but with the pin h', when the detent-lever is raised by the minute-hand shaft. We make one of the wires or runnels j of the pinion K on the shaft L detachable for the purpose of disengaging the pin-wheel J to admit of the adjustment of the pin-wheel J without taking the works apart. The pin is held in its connected position in the heads k k of pinion by means of the wire spring W connected with the shaft L. The construction of the pinion is clearly shown in Fig. 6, in which the runnel j is partly withdrawn to show the manner of breaking the connection between the wheel and pinion. For an accurate adjustment of the dividing-wheel F with the great-wheel E, we connect their plates together by means of a screw, X, which passes through the slot l, which is seen in Fig. 5.

We are aware that it is not new to employ a three-armed lever, one arm of which carries the pins, another arm engages with the dividing-wheel, and the other arm is operated to lift the other two arms.

We therefore claim, as an improvement thereon—

1. The lifting-lever T, consisting of a single

bar, carrying the pins h h' , and formed with the knife-edge f between the pivot and free end of the lever, and having said free end raised by the projection d on the hand-arbor U, when arranged with the dividing-wheel F and wheel M, with its pin i , as herein set forth.

2. The combination of the dividing-wheel F with the great-wheel E by means of the screw X and slot l , as and for the purpose above set forth.

In testimony that the above is our invention we have hereunto set our hands and seals.

GIDEON HOWARD LEEDS. [L. S.]
